UNITED STATES PATENT OFFICE.

SIGMUND M. ROSIN, OF PHILADELPHIA, PENNSYLVANIA.

DESIGN FOR A MATCH-BOX.

SPECIFICATION forming part of Design No. 31,851, dated November 21, 1899.

Application filed October 25, 1899. Serial No. 734,780. Term of patent 3½ years.

To all whom it may concern:

Be it known that I, SIGMUND M. ROSIN, a citizen of the United States, residing in the city and county of Philadelphia, State of Pennsylvania, have invented and produced a new and original Design for a Match-Box, of which the following is a specification, reference being had to the accompanying drawings, forming part thereof.

10 The leading feature of my design for a match-box is a body and a base presenting the appearance of sections of a sea-shell and stripes on said base.

Figure 1 represents a perspective view of a match-box embodying my design. Fig. 2 represents a vertical section thereof.

In the drawings, A designates the body of

the match-box, and B the base thereof, the latter being convex and having the body seated on the crown thereof. The body and base 20 present the appearance of sections of a sea-shell. On the upper face of the base are stripes C, which extend transversely outward from the longitudinally-extending line D.

Having thus described my invention, what 25 I claim as new, and desire to secure by Letters Patent, is—

The design for a match-box, substantially as shown and described.

SIGMUND M. ROSIN.
